(57) **CLAIM**

The ornamental design for an autothrottle for an aircraft as shown and described.

DESCRIPTION

FIG. 1 is a front, top, left side perspective view of an autothrottle for an aircraft showing our new design, shown in a condition of use;

FIG. 2 is a front, top, right side perspective view thereof;

FIG. 3 is a front elevation view thereof;

FIG. 4 is a left side elevation view thereof;

FIG. 5 is a right side elevation view thereof;

FIG. 6 is a top plan view thereof; and,

FIG. 7 is a front, top, left side perspective view thereof. The dashed broken lines depict portions of the autothrottle for an aircraft that form no part of the claimed design. The dashed broken lines in FIGS. 1 to 7 showing a cockpit depict environmental structure that forms no part of the claimed design.
